UNITED STATES PATENT OFFICE.

FRANCIS DE FONTES, OF BALTIMORE, MARYLAND.

BARBER-CHAIR.

SPECIFICATION forming part of Letters Patent No. 637,715, dated November 21, 1899.

Application filed February 23, 1899, Serial No. 706,485. (No model.)

To all whom it may concern:

Be it known that I, FRANCIS DE FONTES, a citizen of the United States, residing at Baltimore, in the State of Maryland, have invented 5 certain new and useful Improvements in Barber-Chairs, of which the following is a specification.

This invention relates to a barber's chair, and has for its object to provide improved 10 mechanism and construction for effecting various adjustments of the body, back, and foot-rest of the chair.

The invention is illustrated in the accompanying drawings, in which—

15 Figure 1 is a vertical elevation of the chair and shows two positions of the parts, one in full lines and the other in broken lines. Fig. 2 is a vertical section of the base center and a part of the revoluble seat-support, taken on 20 the line 2 2 of Fig. 5, which is in a transverse direction from the line on which Fig. 1 is taken. Fig. 3 is a vertical section of the base center and a part of the revoluble seat-support, taken on the line 3 3 of Fig. 5, being in a 25 transverse direction from that shown in Fig. 2. Fig. 4 is a rear view of the depending part of the leg-rest, looking forward. Fig. 5 is a top view of the base center. Fig. 6 is a view of the foot-rest detached, showing the side 30 that would be seen when seated in the chair.

The letter A designates the feet of the base, and A' the base center to which the feet are attached. This base center is hollow in a vertical direction and at its bottom has a contracted portion a, with a round pivot-hole 35 through it for the tubular vertical spindle B. At the top of the base center and made fast thereto is a circular cap-plate b, having a round pivot-hole in its center also for the 40 spindle B and provided with holes c, arranged in a circle around the spindle-hole. The revoluble seat-support C has the depending spindle B attached. The seat-support rests upon the circular cap-plate b. It will be seen 45 that the seat-support C may readily turn in a horizontal plane. The seat-support has at two opposite sides upright standards d, which have pivots d', that support the chair-seat frame D, thus allowing the latter to tilt, as indicated 50 by broken lines in Fig. 1. The seat-support C at the rear has an upward-curved rigid arm C', provided at its top with a slotted guide e

and two rollers or pins e', extending across the slot.

The back E of the chair is pivoted at each 55 side by pivot-pins f to rear-curving arms g on the side arms F, and the said back carries at its lower end a downward-curved rigid arm h, which passes freely in the slotted guide e of the arm C. This down-curved arm h also 60 passes between the said cross-pins e' and at its lower end has a hook h', which serves to limit the forward tilt of the back E on its pivots f by engaging one of the said pins e'. By this construction when the seat-support C 65 and back of the chair are tilted backward the relative position of the back with respect to the seat is automatically changed.

The chair-seat frame D at its front and lower side has a downward-curved rack-bar 70 i, and a pawl-lever G has three arms j j' j'', the lower arm j being secured by a pivot-pin k to the revoluble seat-support C, occupying a slot o in said support, the upper arm j' serving as a pawl to engage the teeth of the said 75 curved rack-bar i, and the rear projecting arm j'' extending directly over the upper end of the tubular vertical spindle B, where it is engaged by a rod l, that extends down through the said spindle. The lower end of this rod 80 l is connected with a treadle-lever H, located below the base center A' and within the space circumscribed by the spreading feet A. The treadle-lever H is pivoted by a joint m to a lateral arm attached to the lower end of the 85 tubular spindle B. A suitable spring n is under the rear projecting arm j'' of the pawl-lever and normally presses said arm upward, and thereby causes the pawl-arm j' to engage the rack-bar i. By depressing the treadle H 90 the pawl-arm j' will release from the rack-bar i, and then the chair-seat frame D may be tilted.

A vertically-movable stop-pin c' is carried by the seat-support C and is arranged to engage any one of the holes c of the circle in the cap-plate b. The stop-pin is seen in Figs. 2 and 3, but is not seen in Fig. 1, because its position on the chair is on the side that is removed in making that sectional view. This 95 stop-pin serves to hold the seat-support and chair-seat from rotating and by its adjustment in different holes c will permit of fixing the chair-seat partly turned in any position.

A horizontal rock-shaft p has two bearings, one at q on an upward-curved arm I , which projects from the side of the revoluble seat-support C , and the other bearing q' on top of the seat-support. The outer end of the rock-shaft p has a crank-arm p' , which has position outside of the seat-frame D . This rock-shaft has a cam r , which takes under a flanged head c^2 on the stop-pin and serves to raise the latter and disengage it from the hole c it may be occupying in the circular cap-plate b . A spiral spring s is around the stop-pin c' and bears downward on a cross-pin s' , which extends through the stop-pin, and thus the said 15 spring s keeps the stop-pin normally pressed down. By throwing the crank-arm p' toward the front to its farthest extent the stop-pin c' may be raised in order to turn the chair on its spindle B . It is to be understood that the 20 seat-support C , seat-frame D , with its rack-bar i , pawl-lever G , vertical rod l , tubular spindle B , and treadle-lever H will all revolve together on the base center A' .

The chair-seat frame D at the front has a 25 rigidly-fixed depending frame comprising two down side bars J and a cross-bar J' , connecting the two. A vertical leg-rest L and horizontal platform N are rigidly connected and form a right angle, as shown in Fig. 1. The 30 leg-rest L is attached between the two side bars J by pivots t , and said leg-rest has no connection with the chair-seat frame other than through the pivots t . The upper end of the leg-rest L is connected with the seat-support C by a link-rod x , whose end is jointed to the leg-rest by a pin x' and to the support by a pin x^2 . This link-rod x serves to tilt the leg-rest relative to the down side bars J when the chair-seat frame D and said side bars are 35 tilted back on pivots d' . The top of the leg-rest in the present instance has a slot i' , which makes room for the curved rack-bar on the chair-seat frame when the chair-body is tilted back, as in broken lines in Fig. 1.

40 At the front edge of the horizontal platform N is a joint u , by which the foot-rest P is pivoted. This foot-rest consists of a suitable cushioned bar or roller mounted on two prongs P' , approximately V -shaped. The united 45 lower ends of these prongs have ears u' , which form part of the said joint. A downward-projecting arm w is rigidly attached at the united ends of the prongs P' , and said arm extends down from the joint and below the 50 horizontal platform N . A link-rod Q , below said platform, connects the down arm w of the foot-rest with the cross-bar J' of the rigid depending frame. The construction here described and shown has the effect to place the 55 foot-rest P in a certain relative position with respect to the leg-rest L when the chair is not tilted, (see full lines in Fig. 1); but when the chair is tilted on its pivots d' then the position of the foot-rest P with respect to the 60 leg-rest L is changed and is farther away from the latter, as indicated by broken lines in the

same figure, so that a person reclining and stretched at full length may have the foot-rest come at the desired distance to properly support the legs. 70

The rock-shaft p has another cam y , which bears upon the rear projecting arm j^2 of the pawl-lever G . This cam is inoperative when the rock-shaft turns forward in the direction to work the other cam r . When turned forward in the inoperative position, a lug y' on the cam comes in contact with the top of a standard z and is thereby prevented from turning any farther; but when the rock-shaft turns in the opposite direction—i. e., backward—80 the cam y forces down the arm j^2 of the pawl-lever and releases the pawl end j' from the rack-bar i . When turned in the backward direction, the rock-shaft and cam r have no effect on the stop-pin c' . Thus the rock-shaft 85 and cam y will serve as a substitute for the treadle-lever mechanism.

Having thus described my invention, what I claim as new, and desire to secure by Letters Patent, is—

1. In a chair the combination of a seat-support, C , having at opposite sides an upright standard, d ; an upward-curved rigid arm, C' , attached at the rear of the seat-support and said arm provided at its top with a slotted guide, e , and two pins extending across the slot; a chair-seat frame secured by pivots, d' , to the said two upright standards and having side arms, F ; a back, E , pivoted to the said side arms; and a downward-curved arm, h , attached by its upper end to the pivoted back and passing freely in the said slotted guide and provided at its lower end with a hook, h' , whereby the relative position of the back with respect to the seat is automatically changed 100 when the chair is tilted, substantially as described.

2. In a chair the combination of a base center having a vertical spindle-hole; a seat-support, C , having a tubular spindle fitting in said hole; a seat-frame, D , pivoted on the seat-support so as to tilt and provided at its front with a downward rock-bar, i ; a pawl-lever, G , having three arms—the lower one pivoted to the seat-support, the upper one 110 serving as a pawl and engaging the said rack-bar, and a rear projecting one having its end over the tubular spindle; a treadle-lever, H , carried by the tubular spindle; a rod, l , within the said tubular spindle and connecting the 115 rear arm of the pawl-lever with the treadle-lever; and a spring, n , under the rear arm of the pawl-lever.

3. In a chair, the combination of a seat-support, C ; a chair-seat frame pivoted on said seat-support so as to tilt; a rigidly-fixed frame attached to the chair-seat frame and comprising two down-projecting side bars, J , and a cross-bar, J' , connecting them; a vertical leg-rest, L , centrally pivoted between the said 120 two down side bars and having a platform, N , rigidly connected and forming a right an-

gle; a link-rod, *x*, connecting the upper end of the leg-rest with the said seat-support whereby the leg-rest will be tilted relative to the down side bars; a foot-rest, *P*, mounted on uprights which are pivoted at the front of the said platform and has an arm, *w*, projecting down below the platform; and a link-rod, *Q*, below the platform connecting the said

arm with the cross-bar, *J'*, of the depending rigid fixed frame.

In testimony whereof I affix my signature in the presence of two witnesses.
